CARBURETOR

Robert F. Bracke, Detroit, Mich.

Application April 13, 1937, Serial No. 136,544

9 Claims. (Cl. 261—72)

My invention pertains to carburetors, and is more particularly concerned with carburetors of the fuel lift type.

In non-fuel lift carburetors for automotive use, it is common to provide a main fuel supply nozzle and an idling jet. This idling jet is customarily located on the engine side of the throttle valve, and takes care of the fuel requirements of the engine during idling operation. A needle valve or other adjustable means is commonly provided to adjust this idling jet. Both the main fuel supply nozzle and the idling jet receive their fuel requirements from the float bowl of the carburetor.

Various attempts have been made to provide a fuel lift carburetor with such an idling jet. In fuel lift carburetors, however, the float bowl of the carburetor is maintained under a degree of suction sufficient to draw fuel thereinto from the main fuel supply tank, usually located at the rear of the automobile. At full throttle operation the degree of suction obtaining in the carburetor float bowl is greater than that obtaining at the discharge end of the idling jet, with the result that back feed of fuel and air occurs from the idling jet to the float bowl of the carburetor. This is disadvantageous in that it destroys the delicate balance necessary to proper operation of a fuel lift carburetor.

An object of my invention is to provide a fuel lift carburetor with an idling jet which overcomes the foregoing disadvantages.

Another object is to provide a fuel lift carburetor with an idling jet whose supply of fuel is cut off by a throttle regulated valve under predetermined conditions.

Another object is to provide a fuel lift carburetor of the dual type, and wherein each of two idling jets is provided with an independent adjustment.

Another object is to provide an idling jet having a control valve mechanism which functions to enrich the mixture supplied to the engine when the throttle valve is opened.

Another object is to provide a carburetor which is simple and economical to manufacture, which will provide long and trouble-free service, and wherein the various control mechanisms may be independently adjusted.

Other objects and advantages will become apparent as the description proceeds.

In the drawings:

Figure 1 is a longitudinal section of a carburetor embodying my invention. This figure is taken on the line 1—1 of Figure 2.

Figure 2 is an irregular horizontal section taken on the line 2—2 of Figure 1.

Figure 3 is a diagrammatic view wherein the relative positions of the parts are distorted but wherein their functional relationship is easier to follow.

Figure 4 is a fragmentary longitudinal section similar to Figure 1, but showing a modified form of my invention. This figure is taken on the line 4—4 of Figure 5.

Figure 5 is a horizontal section taken on the line 5—5 of Figure 4.

I have shown my invention as being embodied in a fuel lift carburetor of the dual type. This carburetor has an air inlet 10 which may be provided with any suitable air cleaner or strainer, and which supplies air to a pair of fuel feeding nozzles 12. Each of these nozzles discharges into a mixing chamber 14, and each mixing chamber communicates with a throttle bore 16 leading to the inlet manifold of the automobile engine.

An air valve 18 controls the supply of secondary air to the mixing chambers 14. In normal operation of the engine the quantity of fuel supplied thereto is variably controlled by a pair of throttle valves 20, which are mounted on a common shaft 22 having attached to one end thereof a lever 24 provided with a ball head 26 adapted for connection to the usual hand and foot controls of the automobile. This lever 24 is further provided with an adjustable screw 28 which engages a stop pin 30 to determine the closed positions of the throttle valves 20.

The two nozzles 12 are supplied with fuel from a common float bowl 32. This float bowl is provided with a threaded inlet 34 adapted to have secured thereto a pipe leading to the main fuel supply tank at the rear of the automobile. Such a pipe is indicated at 36 in Figure 3 of the drawings. The usual inlet valve 38 is provided to regulate the supply of fuel to the float bowl from the main fuel supply tank, this inlet valve 38 being controlled in turn by the float 40 which is pivotally supported at 42.

All fuel passing from the float bowl 32 to the nozzles 12 must pass upwardly through a fixed tube 44 which is threaded secured to the upper casting 46 of the carburetor. This tube leads to a chamber 48 which is connected with the individual nozzles 12, respectively, by way of passages 50 and 52.

Each of the nozzles 12 has a restricted throat terminating in a step 54, and immediately below this step is a series of inclined passages 56 lead-

ing to an annular space 58. This space communicates with one of the passages 50 or 52.

The secondary air valve 18 may be of any suitable type. In the drawings, however, I have shown an air valve consisting of a plate 60 eccentrically mounted on a rod 62 pivotally supported in the casting 46. Attached to this rod 62 are a pair of spaced weights 64 which tend to hold the plate 60 against the shoulder 66. The suction created beneath the plate 60 tends to open this valve against the resistance of the weights 64.

The movements of the air valve 18 are damped by dashpot mechanism comprising a cylinder 68 having a piston 70 reciprocable therein. The piston 70 has a piston rod 72 provided with a slot 74 which receives a pin 76 extending between the two weights 64. Any movement of the air valve 18 thus creates a corresponding movement of the piston 70. In the normal operation of the carburetor the upper end of the cylinder 68 is closed to atmosphere, whereas the lower end of this cylinder is connected to the space beneath the secondary air valve 18 by means of a small opening 78 of a size comparable to that made by a No. 60 drill.

The float bowl 32 is normally maintained under sub-atmospheric pressures by a booster 80. This booster is in the form of a Venturi tube having a restricted throat provided with radial passages 82 communicating through an annular chamber with a duct 84 leading to the top of the float bowl 32. This booster 80 receives its air supply through a port 86 in a shiftable choke plate 88.

When the carburetor is operating under normal conditions, the plate 88 is in the position shown in Figure 1 of the drawings. The port 86 establishes communication between the inlet end of the booster 80 and the chamber 90 formed by a sheet metal cup 92 attached to the lower casting 94 by bolt 96 and spring 98. The chamber 90 in turn communicates with atmosphere through an L-shaped inlet 100.

The booster 80 discharges into the upper end of a cylindrical space 102 which is divided into upper and lower parts by a metal cup 104 having a restricted orifice 106. A tapered pin 108 is located in the orifice 106, and is attached to the lower end of the piston rod 72, whereby this pin shifts its position with the air valve 18. The function of this pin 108 is to regulate the flow of air through the booster 80, and thereby maintain the desired degree of suction in the float bowl 32 under all conditions of carburetor operation.

The lower end of the tubular space 102 is in communication with a duct 110 having branches 112 leading to both mixing chambers 14.

It will be understood that the choke plate 88 is connected to the usual choke control means located on the dash of the automobile, whereby this choke plate may be shifted to facilitate starting of a cold engine. Such shifting of the choke plate 88 restricts or entirely cuts off the air supply to the booster 80, thereby reducing the degree of suction obtaining in the float bowl 32 and permitting the supplying of a richer mixture to the engine than would be possible if the normal degree of suction were maintained in the float bowl 32. When the choke plate 88 is shifted to facilitate cold starting, the port 114 in this plate establishes communication between atmosphere and passage 116 leading to the upper end of the dashpot cylinder 68. Under these conditions the upper surface of the piston 70 is acted upon by atmosphere, whereas the lower surface of the piston is exposed to the suction obtaining in the

mixing chambers 14. This causes the piston 70 to act as an additional means for closing the secondary air valve 18.

Below each throttle valve 20 I provide an idling jet 118. Each idling jet communicates with the lower end of a vertical conduit 120, and is controlled by an adjustable needle valve 122. Each needle valve may be adjusted independently of the other, and is frictionally held in adjusted position by a spring 124. The upper end of each conduit 120 communicates with the float bowl of the carburetor through means which I shall later describe.

Back bleed would occur through an opening 126 to the float bowl of the carburetor if the associated idling jet 118 were cut off entirely by an improper adjustment of its needle valve 122.

In order to prevent such back bleed I provide each throttle bore with an auxiliary idling jet 128. Each auxiliary idling jet 128 communicates with a conduit 120, and is of smaller diameter than its associated opening 126. The size of the auxiliary jets 128, however, is sufficiently large to prevent back bleed through the openings 126 to the float bowl of the carburetor in the event that the main idling jets 118, or either of them, is completely cut off by an improper adjustment of its needle valve 122.

The upper end of each conduit 120 is connected with the lower end of one of the inclined conduits 130 which lead to the opposite ends of a cross passage 132 (Fig. 2). A metal plug having a metering orifice 134 is located adjacent each end of this cross passage 132, and meters the quantity of fuel supplied to the idling jets 118 and 128. The central portion of the cross passage 132 communicates with radial ports 136 formed in a stationary sleeve 138 press-fitted or otherwise secured in the casting 46.

Inside the sleeve 138 there is a sliding tube 140 having radial openings 142 which connect the interior of the tube with the float bowl 32. The sliding tube 140 is also provided with a second series of radial passages 144 connecting the interior of the tube with longitudinal slots 146 communicating with the radial ports 136 in the sleeve 138. When the parts are in the position shown in the drawings, the idling jets 118 and 128 are capable of drawing fuel from the float bowl 32.

In order to prevent siphoning of the fuel from the float bowl through the idling jets when the engine is not operating, I provide the upper end of the sliding tube 140 with a small orifice 148 which functions as an air vent to break up any siphoning action. When the idling jets are operating to supply fuel to the engine, a small amount of air is drawn in through this opening 148 and mixes with the fuel supplied to the idling jets. Additional air is supplied to the idling jets 60 through the openings 126.

I shall now describe the means which I have provided for disconnecting the idling jets from the float bowl of the carburetor when the automobile reaches a speed of approximately twenty-five miles per hour upon a level road and with a normal load. The upper end of the sliding tube 140 threaded engages the lower end of a cap 150 which is pivotally secured to the lower end of a link 152. The upper end of this link is in turn pivoted to the end of an arm 154, non-rotatably secured to a shaft 156 by a pin 158.

The shaft 156 is rotatably supported in bearings provided by the upper casting 46, and one end of the shaft 156 extends outside of the cast-75

ing 46 and has loosely mounted thereon a lever 160 which is connected by a rod 162 with the throttle valve lever 24. A second lever 164 is non-rotatably secured to the projecting end of the shaft 156. The levers 160 and 164 are adjustably connected by means of a screw 166 which is held in adjusted position by a spring 168, which also eliminates any slack in the connection between the levers 160 and 164.

When the throttle valves 20 are opened to a position corresponding to a car speed of twenty-five miles an hour on a level road with a normal load, the sliding tube 140 is raised to such a height that the ports 142 in the lower part of this tube are closed by the lower end of the stationary sleeve 138, and thus all communication between the idling jets and the interior of the float bowl 32 is cut off. The speed at which this cut-off occurs can be varied by adjusting the screw 166. The sliding tube 140 is urged downwardly by a coil spring 170 which is interposed between the upper casting 46 and a bar 172 carried by the lower end of the tube 140.

This bar 172 also carries and reciprocates a metering pin 174. This metering pin 174 has a relatively large cylindrical upper end 176 which, during idling operation of the engine, is located in a restricted opening 178 formed in the tube 44, and thereby reduces the amount of fuel supplied to the nozzles 12. This cylindrical portion of the metering pin 174 is made of appreciable length so that adjustment of the cut-off position for the idling jets does not vary the quantity of fuel supplied to the nozzles 12 during idling operation of the engine. Below the cylindrical portion 176 of the metering pin there is a tapered portion 180 which varies the amount of fuel supplied to the nozzles 12 when the engine is operating above idling speed but below approximately three-quarters full throttle. When the throttle valves are opened through three quarters of their full range, the small cylindrical part 182 of the metering pin is located in the opening 178 and permits free flow of fuel to the nozzles 12.

The central position of the metering pin relative to the orifice 178 is determined by a guide portion 184 which is located in the lower end of the tube 44. This guide portion has a passageway 186 which permits fuel to flow past the guide portion.

The bar 172 also supports and actuates the piston 188 of an accelerator pump. This piston 188 is located in a cylinder 190 which extends down into the float bowl 32 of the carburetor, and is secured to the upper casting 46 by a threaded plug 192. The piston includes a leather cup washer 194 whose lip is pressed against the cylinder wall by a coil spring 196.

The piston 188 has a hollow central portion 198 which communicates with the interior of the float chamber through passages 200 and with the interior of the cylinder 190 by way of valve 202. The valve 202 is limited in its movement by a cross pin 204.

The piston 188 has a reduced stem 206 which is slidably received in an opening in the bar 172. The piston 188 is urged upwardly by a coil spring 208, the upward movement of the piston under the influence of this spring being limited by a washer 210 secured to the lower end of the stem 206.

When the throttle valves are opened, the bar 172 is raised and the piston 188 is moved upwardly. This upward movement forces fuel from the cylinder 190 upwardly through the passage

212 and past the check valve 214 which is normally held against its seat by a spring 216 resting against a support 218. The fuel forced past the valve 214 flows through passageways 220 to accelerating nozzles 222. Each nozzle 222 comprises a tubular piece of metal having a restricted discharge opening.

When the throttle valves are opened slowly, the spring 208 beneath the accelerator pump piston does not compress, and this piston advances 10 at the same rate as the bar 172. However, when the throttle valves are suddenly opened through an appreciable range of movement, the resistance offered by the fuel above the accelerator pump piston 188 causes the spring 208 to compress so 15 that the accelerator pump piston does not move upwardly as fast as its actuating bar 172. After the actuating bar 172 stops its upward movement, the spring 208 expands and continues the upward movement of the piston 188. In this manner the 20 injection of the accelerating charge is prolonged beyond the opening movement of the throttle valves.

In my improved carburetor the idling jets also furnish additional fuel to the engine during an 25 opening movement of the throttle valves which takes place within the operating range of the idling jets, that is, before these jets have been cut off from communication with the float chamber of the carburetor. During the normal operation of the idling jets, the fuel in the slots 146 of the sliding tube 140 does not rise above the ports 136 in the sleeve 138, and a mixture of fuel and air flows through these ports to the idling jets. When the throttle valves are opened suddenly, the 30 sliding tube 140 is suddenly raised, and the liquid fuel in the lower ends of the slots 146 is likewise suddenly raised so that it completely cuts off all air from the ports 136. Under the temporary condition thus created, only liquid fuel undiluted by 35 air passes through the ports 136 to the idling jets, thereby enriching the mixture supplied by these jets to the internal combustion engine.

When the engine is idling, the secondary air valve 18 is closed, and most of the air entering 45 the mixing chambers 14 flows through the nozzles 12. During the idling operation these nozzles draw little or no fuel from the float chamber 32. The throttle valves 20 are practically closed, and the mixing chambers are under a pressure only 50 slightly below atmospheric.

The idling jets 118 and 128 are located on the engine side of the throttle valves, and are subjected to the high suction obtaining in the engine manifold. These idling jets draw fuel from the 55 float chamber of the carburetor. The fuel which is withdrawn from the float chamber is mixed with a slight amount of air drawn into the vent 148 at the upper end of the sliding tube 140. Additional air is supplied through openings 126 60 for mixture with this fuel before it is discharged through the idling jets 118 and 128. Even during idling operation, the throttle valves 20 are not entirely closed, and a slight amount of air 65 flows therepast for mixture with the fuel supplied through the idling jets. The richness of the mixture supplied by each idling jet may be independently adjusted by regulating its associated needle valve 122.

During this idling operation of the engine, the float bowl 32 of the carburetor is maintained under subatmospheric pressure by the booster 80. This booster receives atmospheric air by way of inlet 100 and chamber 90, and discharges into the mix- 75

ing chambers 14, thereby supplying additional air thereto. The throat of the booster 80 is connected by means of radial ports 82 and passage 84 with the upper end of the float chamber 32 to withdraw air and vapor therefrom.

The degree of suction maintained in the float chamber by the booster 80 is regulated in part by the tapered pin 108 which varies the flow through the booster 80 and thereby varies the suction created by this booster. Under all ordinary conditions of engine operation the degree of suction in the float bowl is sufficient to draw fuel thereinto from the main fuel supply tank, normally located at the rear of the automobile. During starting of a cold engine the booster 80 may be rendered entirely ineffective by shifting the choke plate 88 so that the inlet to the booster is cut off. Such shifting of the choke plate also admits atmospheric air to the upper end of the dash-pot cylinder 68, and this air acts upon the piston 70 more firmly to urge the secondary air valve 18 toward closed position. Such positioning of the choke plate, however, is used only during starting and while the engine is still cold.

As the throttle valves 20 are opened to cause the engine to operate at speeds faster than idling speed, the nozzles 12 become effective to furnish greater and ever greater proportions of the fuel requirements of the engine. When the engine is operating at a speed of approximately twenty-five miles per hour on a level road and under normal road conditions, the nozzles 12 assume the entire burden of furnishing all of the fuel requirements of the engine. At this point the sliding tube 140 has moved upwardly to such a position that the ports 142 are closed by the lower end of the sleeve 138, thereby cutting off communications between the idling jets and the carburetor float bowl and rendering these idling jets inoperative. This same opening movement of the throttle valves raises the metering pin 174 in its associated orifice 178 so that it offers less restriction to the flow of fuel to the nozzles 12.

If the throttle valves are opened suddenly for the purpose of affording rapid engine acceleration, the piston 188 of the accelerator pump forces fuel into the mixing chamber through the accelerating nozzles 222. Where the accelerating movement of the throttle valves is sudden, the spring 208 which actuates the accelerator pump piston compresses, and the pumping action of the accelerator pump piston is prolonged beyond the opening movement of the throttle valves. This prevents choking of the engine by the too sudden supply of a large quantity of fuel through the accelerating nozzles. Upon a subsequent closing of the throttle valves, the accelerator pump piston descends in its cylinder, and during this movement the valve 202 opens to admit fuel to the cylinder 190 above the accelerating pump piston. Where a sudden opening movement of the throttle valves occurs within the range of operation of the idling jets, the sudden upward movement of the sliding tube 140 carries undiluted liquid fuel above the ports 136 leading to the idling jets. This temporarily provides the idling jets with additional quantities of fuel which facilitate the accelerating action of the engine.

When the throttle valves 20 are opened, the degree of suction obtaining in the mixing chambers is increased sufficiently to open the secondary air valve against the closing action of the weights 64. As the throttle valves 20 are opened wider, the secondary air valve 18 also increases its opening to admit additional air therewith. When the

throttle valves are fully opened, the secondary air valve 18 is also opened to its fullest extent.

When the throttle valves 20 are fully opened, the degree of suction obtaining in the mixing chambers 14 is the same as that obtaining at the outlets to the idling jets which are located below these throttle valves. During such full throttle operation the idling jets and openings 126 are exposed to a degree of suction which is less than that existing in the float bowl 32, but no back bleed to the float bowl can occur because the communication between the float bowl and the openings 126 and idling jets 118 and 128 have been cut off by the movement of the sliding tube 140. The point at which this cut-off occurs can be regulated by adjusting the screw 166. Such regulation of the cut-off does not vary the operation of the accelerator pump, nor does it change the resistance of the economizer pin 174 to fuel feed to the main nozzles 12 during idling operation of the engine.

The embodiment of my invention shown in Figures 4 and 5 is identical with that shown in Figures 1 and 2 except for the arrangement of the idling jets and their supply conduits. It will therefore only be necessary to describe the different idling jets and supply means disclosed in the modification of Figures 4 and 5.

As shown most clearly in Figure 4, each idling jet in this embodiment of my invention comprises a single inclined outlet passage 118' which receives its supply of fuel and air from a vertical conduit 120'. This conduit has an air inlet 126 communicating with a mixing chamber of the carburetor. The upper end of each conduit 120' is connected by a transverse port 129 with a horizontal passage 130' which connects with one end of the cross passage 132.

The central portion of passage 132 communicates with the interior of the tube 138' by way of ports 136'. The tube 138' has a larger bore 139' which communicates with the float bowl of the carburetor by way of a smaller bore 141'. A solid rod 140' extends through the tube 138' and has its upper end attached to the cap 150. The lower end of this rod carries a bar 172. The rod 140' has a groove 143' which maintains communication between the float bowl of the carburetor and the larger bore 139' when the automobile engine is idling or driving the automobile at speeds below 15 miles per hour and under normal load.

In this embodiment of my invention the needle valve 122 for controlling each idling jet is so located that it controls the admission of liquid fuel to the transverse port 129. Each needle valve is maintained in adjusted position by its associated spring 124. I have found that where the needle valves for controlling the idling jets are so arranged that they regulate the flow of liquid fuel only instead of a mixture of fuel and air, more stable engine operation is obtained at idling speeds.

In order to prevent siphoning of the fuel through the idling jets when the engine is at rest, I provide the upper end of each conduit 120' with a very small duct 145' which connects with a secondary air inlet just below a secondary air valve. In practice I have obtained excellent results where the ducts 145' are made with a No. 75 drill, the openings 126 with a No. 70 drill, and the idling jets 118' with a No. 65 drill.

Subject matter disclosed but not claimed herein is claimed in my copending application Serial No. 273,853, filed May 16, 1939.

While I have disclosed only a single embodiment of my invention, it is to be understood that my invention may assume numerous forms and that the scope of my protection is limited solely by the following claims.

I claim:

1. In a fuel lift carburetor of the class described, the combination of a nozzle, a float chamber from which said nozzle is supplied with fuel, a mixing chamber into which said nozzle discharges, a throttle valve associated with said mixing chamber, an idling jet below said throttle valve, conduit means including a valve for connecting said idling jet with said float chamber, an operating connection between said last mentioned valve and said throttle valve, an accelerating nozzle discharging into said mixing chamber, an accelerating pump connected with said accelerating nozzle, economizer means interposed between said first mentioned nozzle and said float chamber, means connecting said conduit valve with said economizer means and accelerator pump, and a booster for maintaining said float chamber under subatmospheric pressure.
2. In a fuel lift carburetor of the class described, the combination of a nozzle, a float chamber from which said nozzle is supplied with fuel, means including a metered orifice connecting said nozzle with said float chamber, an economizer pin located in said orifice, said economizer pin having a cylindrical part restricting flow of fuel to said nozzle during idling operation of an engine to which said carburetor is attached, an idling jet, conduit means connecting said idling jet with said float chamber, a valve in said conduit means automatically operative to cut off said idling jet from said float chamber when a predetermined condition of carburetor operation is reached, means connecting said economizer pin with said valve for movement therewith, means for adjusting said valve without disturbing the restrictive function of said economizer pin during idling operation of the engine, means for operating said valve and economizer pin, and a booster for maintaining said float chamber under sub-atmospheric pressure.
3. In a fuel lift carburetor of the class described, the combination of a float bowl adapted to hold a quantity of fuel, means for maintaining said float bowl under sub-atmospheric pressure, a main nozzle supplied with fuel from said float bowl, a conduit connecting said nozzle with said float bowl, said nozzle being capable of drawing fuel from said float bowl under all conditions of carburetor operation, an idling jet supplied with fuel from said float bowl, a second conduit connecting said idling jet with said float bowl, the absolute pressure in said idling jet being greater under certain conditions of carburetor operation than the absolute pressure in said float bowl whereby under said conditions of carburetor operation back bleed into said float bowl through said second conduit would normally occur, valve means controlling communication between said float bowl and idling jet, and automatic means operable upon creation of a pre-determined condition of carburetor operation to close said valve and prevent back bleed into said float bowl.
4. In a fuel lift carburetor of the class described, the combination of a float bowl adapted to hold a quantity of fuel, means for maintaining said float bowl under sub-atmospheric pressure, a main nozzle supplied with fuel from said float bowl, a conduit connecting said nozzle with said float bowl, said nozzle being capable of drawing

fuel from said float bowl under all conditions of carburetor operation, an idling jet supplied with fuel from said float bowl, a second conduit connecting said idling jet with said float bowl, the absolute pressure in said idling jet being greater under certain conditions of carburetor operation than the absolute pressure in said float bowl whereby under said conditions of carburetor operation back bleed into said float bowl through said second conduit would normally occur, valve means controlling communication between said float bowl and said second conduit to prevent back bleed therethrough, a throttle valve controlling communication between said main nozzle and an internal combustion engine to which said carburetor is attached, and a connection between said throttle valve and said first-mentioned valve to close the latter when said throttle valve is opened a predetermined amount.

5. In a fuel lift carburetor of the class described, the combination of a float bowl adapted to hold a quantity of fuel, means for maintaining said float bowl under sub-atmospheric pressure, a main nozzle supplied with fuel from said float bowl, a conduit connecting said nozzle with said float bowl, said nozzle being capable of drawing fuel from said float bowl under all conditions of carburetor operation, an idling jet supplied with fuel from said float bowl, a second conduit connecting said idling jet with said float bowl, said second conduit having an air inlet, the absolute pressure in said idling jet being greater under certain conditions of carburetor operation than the absolute pressure in said float bowl whereby under said conditions of carburetor operation back bleed into said float bowl through said second conduit would normally occur, valve means in said second conduit to prevent back bleed therethrough, said valve means being located between said float bowl and said air inlet, a throttle valve controlling communication between said main nozzle and an internal combustion engine to which said carburetor is attached, and a connection between said throttle valve and said first-mentioned valve to close the latter when said throttle valve is opened a predetermined amount.

6. In a fuel lift carburetor of the class described, the combination of a float bowl adapted to hold a quantity of fuel, means for maintaining said float bowl under sub-atmospheric pressure, a main nozzle supplied with fuel from said float bowl, a conduit connecting said nozzle with said float bowl, said nozzle being capable of drawing fuel from said float bowl under all conditions of carburetor operation, an idling jet supplied with fuel from said float bowl, a second conduit connecting said idling jet with said float bowl, the absolute pressure in said idling jet being greater under certain conditions of carburetor operation than the absolute pressure in said float bowl whereby under said conditions of carburetor operation back bleed into said float bowl through said second conduit would normally occur, valve means for closing said second conduit to prevent back bleed therethrough, said second conduit having a portion located above said valve, a throttle valve controlling communication between said main nozzle and an internal combustion engine to which said carburetor is attached, and a connection between said throttle valve and said first-mentioned valve to close the latter when said throttle valve is opened a predetermined amount.

7. In a fuel lift carburetor of the class described, the combination of a float bowl adapted

to hold a quantity of fuel, means for maintaining said float bowl under sub-atmospheric pressure, a main nozzle supplied with fuel from said float bowl, a conduit connecting said nozzle with said float bowl, said nozzle being capable of drawing fuel from said float bowl under all conditions of carburetor operation, an idling jet supplied with fuel from said float bowl, a second conduit connecting said idling jet with said float bowl, the absolute pressure in said idling jet being greater under certain conditions of carburetor operation than the absolute pressure in said float bowl whereby under said conditions of carburetor operation back bleed into said float bowl through said second conduit would normally occur, valve means in said float bowl for closing said second conduit to prevent back bleed therethrough, a throttle valve controlling communication between said main nozzle and an internal combustion engine to which said carburetor is attached, and a connection between said throttle valve and said first-mentioned valve to close the latter when said throttle valve is opened a predetermined amount.

8. In a fuel lift carburetor of the class described, the combination of a float bowl adapted to hold a quantity of fuel, means for maintaining said float bowl under sub-atmospheric pressure, a main nozzle supplied with fuel from said float bowl, a conduit connecting said nozzle with said float bowl, said nozzle being capable of drawing fuel from said float bowl under all conditions of carburetor operation, an idling jet supplied with fuel from said float bowl, a second conduit connecting said idling jet with said float bowl, said second conduit having a portion located above the fuel in said float bowl, the absolute pressure in said idling jet being greater under certain conditions of carburetor operation than the absolute pressure in said float bowl whereby under said conditions of carburetor operation back bleed into said float bowl through said second con-

duit would normally occur, valve means in said float bowl for closing said second conduit to prevent back bleed therethrough, said valve means being submerged in the fuel in said float bowl, a throttle valve controlling communication between said main nozzle and an internal combustion engine to which said carburetor is attached, and a connection between said throttle valve and said first-mentioned valve to close the latter when said throttle valve is opened a predetermined amount. 5 10

9. In a fuel lift carburetor of the class described, the combination of a float bowl adapted to hold a quantity of fuel, means for maintaining said float bowl under sub-atmospheric pressure, a main nozzle supplied with fuel from said float bowl, a conduit connecting said nozzle with said float bowl, said nozzle being capable of drawing fuel from said float bowl under all conditions of carburetor operation, an idling jet supplied with fuel from said float bowl, a second conduit connecting said idling jet with said float bowl, the absolute pressure in said idling jet being greater under certain conditions of carburetor operation than the absolute pressure in said float bowl whereby under said conditions of carburetor operation back bleed into said float bowl through said second conduit would normally occur, valve means in said float bowl for closing said second conduit to prevent back bleed therethrough, said valve means comprising a pair of telescopic tubes, a throttle valve controlling communication between said main nozzle and an internal combustion engine to which said carburetor is attached, and an adjustable spring tensioned connection between said throttle valve and one of said telescopic tubes to close the valve formed by said tubes when said throttle valve is opened a predetermined amount. 15 20 25 30 35 40
